United States Patent [19]

Moses et al.

[11] Patent Number: Des. 281,009

[45] Date of Patent: ** Oct. 15, 1985

[54] **THERMOPLASTIC PANEL FOR STORING A THERMAL ENERGY STORAGE MATERIAL**

[75] Inventors: **Paul J. Moses; James E. Kosinski; Wayne R. Hutter, all of Midland, Mich.**

[73] Assignee: **The Dow Chemical Company, Midland, Mich.**

[**] Term: **14 Years**

[21] Appl. No.: **494,477**

[22] Filed: **May 13, 1983**

[52] U.S. Cl. **D23/72; D25/80**

[58] Field of Search **126/400, 430, 436; D25/80; D23/72, 73, 137, 127**

Attorney, Agent, or Firm—Nis H. Juhl

[57] **CLAIM**

The ornamental design for a thermoplastic panel for storing a thermal energy storage material, as shown.

DESCRIPTION

FIG. 1 is a front perspective view of a thermoplastic panel for storing a thermal energy storage material showing my new design;

FIG. 2 is a rear perspective view of the container or panel;

FIG. 3 is a cross-sectional view taken along line 3—3 of FIG. 1.
